UNITED STATES PATENT OFFICE.

EDWIN BALTZLEY, OF WASHINGTON, DISTRICT OF COLUMBIA.

TRAVELING CONVEYER.

SPECIFICATION forming part of Letters Patent No. 739,574, dated September 22, 1903.

Application filed July 3, 1903. Serial No. 164,109. (No model.)

To all whom it may concern:

Be it known that I, EDWIN BALTZLEY, a citizen of the United States, and a resident of Washington, in the District of Columbia, 5 have invented certain new and useful Improvements in Traveling Conveyers, of which the following is a specification.

This invention relates to escalators and similar traveling conveyers of that type in 10 which a series of steps or treads forming or connected to an endless belt is propelled continuously in a predetermined path in such manner that a person standing on one of the tread-surfaces will be carried thereby from 15 one point to another without effort on his part.

My present improvements are primarily intended to facilitate the safe landing of passengers from the traveling structure and are 20 herein shown and described as applied to an escalator in which the tread-surfaces are grated and are arranged to interleave with a stationary grated landing at the point where passengers are landed and in which the horizontal speed of the grated tread-surfaces is 25 reduced just before they disappear through the landing for the purpose of diminishing the shock and change of motion imparted to the passengers, such an escalator being described and claimed in another application 30 for Letters Patent filed by me on the 3d day of July, 1903, Serial No. 164,108. It is to be understood, however, that my present improvements are not necessarily limited to such 35 an escalator, but are capable of wider application and use and are susceptible of various modifications in structure and general arrangement.

According to my present invention I provide 40 means whereby each tread-surface of the traveling conveyer is caused to incline forwardly and downwardly at what I term a "safe" unloading angle just before it disappears beneath the stationary landing, so that a 45 passenger standing on the tread is slightly tilted forwardly and receives an impulse or suggestion which impels him to step naturally onto the landing in a forward direction, thus effecting his removal from the moving tread 50 and causing him to make way for succeeding passengers with little or no voluntary effort on his part. It is ordinarily desirable to land the

passenger immediately after he reaches the floor-level of an escalator, for that is the psychologic instant for landing, and the passenger 55 naturally follows the sequential movements of a finished ride on the incline by stepping off the escalator and walking away in the forward direction open to him. If the act of landing is delayed beyond this point, an act 60 of decision is involved in determining when to get off the moving tread, which is more or less confusing, especially when the escalator is crowded with passengers. By my invention the proper instant for landing is determined for the passenger and suggested to him, and this may be done at any desired point; but I prefer to impart this landing impulse as soon as the floor-level is reached, because 70 in such case it coincides with and is assisted by the natural inclination of the passenger to leave the moving tread. My present improvements also include certain constructional features and details, hereinafter described. 75

An escalator embodying my improvements in their preferred form is illustrated in the accompanying drawings, which are largely diagrammatic in character and are not intended to represent the exact details of commercial construction. 80

In the drawings, Figure 1 is a side elevation of the moving parts at the upper end of the escalator, together with the stationary upper landing. Fig. 2 is a similar view, on 85 a smaller scale, showing the landing and the guideways for the moving steps. Fig. 3 is a view similar to Fig. 1, but illustrating the lower end of a descending escalator and the adjacent landing; and Fig. 4 is an elevation 90 of the corresponding guideways. Fig. 5 is a transverse section through the guideways at one side of the escalator, showing also the relation of the moving steps thereto and to the upper landing. Fig. 6 is a detail perspective view of an interleaving segment of a step. Fig. 7 is a perspective view of the parts of an end step-segment taken apart and disposed in a group. Fig. 8 is a section through one of the steps from end to end, and Fig. 9 is a similar view showing a modified form of step. Fig. 10 is a perspective view of a link suitable for connecting the steps. Fig. 11 is a detail plan view of a portion of 100

a grated landing, and Fig. 12 is a section on the line $\alpha\alpha$ in Fig. 11.

In its general structure and arrangement the escalator shown in the drawings is like 5 one of the structures shown and described in my application for Letters Patent above referred to except in so far as modifications are introduced by my present improvements and comprises a number of steps or tread-sections 10 2, each of which is pivotally connected to an endless belt composed of pivotally-connected links 3, so that the steps provide in their operation an endless series of tread-surfaces. This belt preferably consists of two or more 15 chains of links, so that if a link in one chain breaks the remaining chain or chains will hold the steps in proper relation. The endless series of links and steps passes over two sprocket-wheels located, respectively, at the 20 upper and lower ends of the escalator and is driven by power applied to one or both of the sprocket-wheels in any suitable manner. In Fig. 1 of the drawings the upper sprocket-wheel 4 is shown as the driving-wheel, being 25 provided with spurs or teeth 5, each adapted to enter a socket 6, cut in each of the links when driving the endless belt in one direction and to enter the mortises 7 in said links when driving the belt in the opposite direction. Fig. 1 of the drawings shows the upper end of an ascending escalator, and Fig. 3 shows the lower end of a descending escalator, the lower sprocket-wheel being represented at 8.

30 The construction and arrangement of the taking-on landings are not material to my present improvements, and hence these landings are not illustrated, their general arrangement being well understood.

35 Each of the steps 2 is so connected to the endless belt that it is capable of independent pivotal movement sufficient to enable it to assume various angles with respect to the path of the belt, and thus to follow guides or 40 guideways for maintaining the tread-surfaces in the desired position. In the drawings the shorter side of each step is shown as pivoted near its bottom to two adjacent links at the 45 point where the latter are pivoted together 50 by means of an axis 9, extending from one end of the step to the other and secured thereto, the links being located between the downwardly-extending ends of the steps.

The tread-surfaces of the several steps are 55 grated, as shown in Figs. 5, 8, and 9, and near the upper end of the ascending escalator is located a grated landing 10, adapted to interleave with the grated steps successively. A similar grated landing 11 is located near 60 the lower end of the descending escalator. The steps 2 are guided in their travel, and their tread-surfaces are kept level between the landings by means of guideways 12 and 13, in which travel antifriction-rollers 14 and 65 15, journaled on the ends of each step near its front and rear sides, respectively. In Fig. 8 these rollers are shown as journaled on axes

extending from end to end of the steps, one of these axes being the axis 9, above referred to, and in this case each link 3 is provided with a recess 16 to receive the axis at the free side of the corresponding step and provide for the required pivotal movement thereof. In Fig. 9 the axes of the rollers 15 at the free side of the step are secured to the ends of the step, thus leaving a free space between said ends sufficient to provide for the pivotal movements above referred to. The guideways 12 and 13 are located outside of the vertical plane of the ends of the steps, as shown in Fig. 5, and one of them, as 13, is contained within the boundaries of the other, being narrower than the latter and extending farther inward. These guideways coincide with each other in direction on the ascending or descending incline; but at the ends of the incline these guideways diverge, as hereinafter described.

The path of the steps as they reach the landing toward which they are moving is such that the grated treads enter the landing at a distance above the surface of the latter and subsequently pass down through the same, so that a passenger is automatically deposited on the landing without previous contact of his feet therewith, and shortly before a tread-surface reaches the plane of the surface of the landing said tread-surface is caused to tilt forwardly and downwardly to a safe unloading angle. This inclination of the tread-surface gives notice to the passenger that the time of landing has arrived and imparts to him a physical impulse, as well as a suggestion, to step forward from the tread upon the landing, and he is thus impelled to remove himself from the path of the next succeeding step and out of the way of any passenger who may be thereon. In case the passenger fails to step forward from the inclined tread-surface he is immediately deposited involuntarily upon the landing, and the step is preferably made to return to its normal horizontal position just before it disappears through the surface of the landing in order to cause the entire bottom surface of the feet of the passenger to come in contact with the landing at the same instant in case he has not previously stepped off the moving tread-surface. These results are accomplished according to the constructions shown in the drawings by causing the guideways 12 and 13 to diverge when a landing is reached in such manner as to impart the desired angle to the tread-surface of each step shortly before it passes down through the landing.

125 The sprocket-wheels 4 and 8 are shown as six-spoke sprocket-wheels, the spokes of which are separated at their extremities by a distance equal to the depth of a step along a line joining its journal-centers, and such a sprocket-wheel is well suited to take up the successive steps and become their guide as they reach the top of the ascending incline and tilt their tread-surfaces to the proper un-

loading angle as they pass successively over the top of the sprocket-wheel, as indicated in dotted lines in Fig. 1. As soon as this dotted-line position has been reached by a step 5 the guideway 13 diverges from its companion guideway, as at 17, Fig. 1, and draws the free side of the step downward at a rate just sufficient to restore its tread-surface to the horizontal position just before it passes downward 10 through the surface of the landing, and said guideway 13 then continues in a path substantially concentric with the axis of the sprocket-wheel, and finally merges into its lower or return portion between the upper 15 and lower sprocket-wheels. At the lower end of the descending escalator the tilting of the steps is accomplished, as illustrated in Fig. 3, by causing the inner guideway 13 to diverge outwardly from the circumference of the 20 sprocket-wheel 8, as at 18, and then to return to the sprocket-wheel along a downwardly-extending path 19. With the construction shown in Fig. 3 the tread-surfaces are not restored to the horizontal position prior to 25 passing through the landing after having been tilted.

I do not limit myself to the employment of a six-spoke sprocket-wheel for tilting the steps to the proper unloading angle, as the 30 same result may be secured by various other means; but when such wheels are employed it is not essential that there should be any guideway for the journaled sides of the steps from the point at which they are engaged 35 by the wheel onto the sprocket-wheel at the other end of the escalator, because at this point the sprocket-wheel itself takes up the belt and the journaled sides of the steps and becomes a guide therefor, and the outer guideway 40 12 may be widened at this point to free it from all frictional contact with the rollers carried by the steps; but in practice I prefer to make the guideways continuously operative, so as to control the steps thereby 45 throughout their travel. The inner guideways especially should be continuously operative throughout the path of the belt for the purpose of preventing the rollers 14 from getting into them. To this end also the rollers 50 14 are preferably made somewhat larger than the rollers 15.

The forward upper corners of the steps are shown in Fig. 1 as beveled, as at 20, in order to provide against any possible danger of an 55 advancing step striking the heel of a passenger after he has landed in case he has failed to walk forward out of its path. This bevel is sufficient to pass under the heel of a passenger and lift his foot by a wedging action 60 until the step has disappeared beneath the grating.

The constructions above described not only provide for tilting the successive tread-surfaces just before the instant for landing is 65 reached, but also serve to reduce the horizontal speed of said tread-surfaces prior to landing a passenger, as fully described in my

other application previously referred to, thus providing for the safe and gentle landing of the passenger without subjecting him to an 70 excessive and confusing change of motion, and my present improvements are preferably, though not necessarily, combined and employed in connection with the feature just referred to.

Figs. 6, 7, and 8 show details of a preferred construction of grated step in which each interleaving segment is composed of two halves 21 and 22, preferably stamped from sheet metal and having flanges at their side 80 and bottom edges formed to fit one into the other and adapted to be riveted or otherwise connected together. Each of the portions 21 and 22 is shown as provided with a rib 23, forming a ledge to support a cushion-tread 24, 85 made of rubber or other suitable material. 25 represents another rib stamped in the parts 21 and 22, but of less depth than the ribs 23, the function of the ribs 25 being to bite into the tread-piece 24 and hold it in 90 place. These interleaving segments are suitably spaced apart by bars 26, and the parts of the step are bound together by tie-rods 27.

Figs. 11 and 12 show a preferred construction of a grated landing in which the bars 28 95 of the landing are recessed on the upper sides to receive tread-pieces 29, which may be held in place by crimping the sides of the bars inwardly against them, as at 30.

I claim as my invention—

1. The combination, with a series of treads forming an endless belt, and means for propelling the same, of a landing, and means for tilting each tread-surface to a safe unloading angle just before it passes beneath said landing.

2. The combination with a series of grated treads forming an endless belt, and means for propelling the same, of a grated landing adapted to interleave with the grated treads 110 successively, and means for tilting each tread-surface to a safe unloading angle while interleaved with said landing.

3. The combination with a series of grated treads forming an endless belt, and means for propelling the same, of a grated landing, means for causing said treads to interleave with the landing with their tread-surfaces above the surface of the latter, means for tilting each tread-surface successively to a safe 120 unloading angle while so interleaved, and means for drawing said tread-surface downward through the landing.

4. The combination with a series of treads forming an endless belt, and means for propelling the same, of a landing, means for tilting each tread-surface successively to a safe unloading angle at a point adjacent to said landing, and means for subsequently restoring said tread-surface to a horizontal position 125 prior to its passing beneath the landing.

5. The combination with a series of grated treads forming an endless belt, and means for propelling the same, of a grated landing adapt-

ed to interleave with said treads successively, means for tilting each tread-surface to a safe unloading angle while interleaved with the landing, and means for subsequently restoring said surface to a horizontal position prior to its disappearance through the landing.

6. The combination with a series of steps forming an endless belt, and means for propelling the same up an incline, of a landing located adjacent to the upper end of the incline, and a six-toothed sprocket-wheel arranged to take up said steps successively at the upper end of said incline and carry them to the landing position.

15. 7. The combination with a series of steps forming an endless belt and inclined guideways therefor, of a landing located adjacent to the upper end of the incline, and a sprocket-wheel so related to said incline that said belt is first engaged by the sprocket-wheel when the ends of the two uppermost arms thereof are in the same horizontal plane.

8. The combination with a series of grated treads forming an endless belt, and means for propelling the same, of a grated landing adapted to interleave with the grated treads successively, and guides for said treads, said guides being formed to tilt each tread-surface to a safe unloading angle and subsequently to withdraw it through said landing.

9. The combination with a series of grated steps forming an endless belt, and means for propelling the same up an incline, of a grated landing located adjacent to the upper end of the incline and adapted to interleave with said grated steps, and a sprocket-wheel carrying said belt and located beneath said land-

ing, said sprocket-wheel being composed of six spokes separated at their outer ends by a distance substantially equal to the depth of a 40 step along a line joining its journal centers.

10. In an escalator, the combination with a series of grated steps forming an endless belt, and means for operating the same, of a grated receiving-landing located at the immediate 45 upper delivery end of the incline and arranged to interleave with said steps successively, said grated steps having a descending and disappearing movement beneath the landing, independent of the direction of movement of the endless belt.

11. In a traveling conveyer, the combination of an endless belt composed of connected links, each link being provided with a recess 16, and a series of steps each pivoted at one 55 side to the connected ends of adjacent links.

12. In a traveling conveyer, the combination with an endless belt, of a series of steps each pivoted at its rear side to said belt, with reference to the direction of its movement, 60 and having its forward end free.

13. A step for a traveling conveyer, comprising spaced segments each composed of box-like side pieces secured together and provided with ribs, and a tread-piece held between said side pieces at their upper ends and supported by said ribs.

In testimony whereof I have hereunto subscribed my name this 1st day of July, 1903.

EDWIN BALTZLEY.
